HAND LUGGAGE

George Henry Wheary, Racine, Wis., assignor to
Wheary Trunk Company, Racine, Wis., a corporation of Wisconsin

Application July 5, 1934, Serial No. 733,823

6 Claims. (Cl. 190—41)

This invention relates to improvements in hand luggage and has as an object to provide an inexpensive and exceptionally light piece of luggage having substantial capacity for carrying various

articles of wear and other personal effects besides means for carrying garments such as men's suits, and ladies' dresses in neatly folded arrangement.

Like the copending application of George Henry Wheary, Serial No. 733,822, filed July 5,

1934, this invention differs from past hand luggage primarily in the fact that men's suits and ladies' dresses are so carried that they are partially within the box and partially on the outside thereof; and it is a particular object of this invention to provide luggage in which one wall, namely the one covering the portions of the garments disposed on the outside of the box, is flexible.

More specifically, it is an object of this invention to provide hand luggage of the character described, wherein a solid walled box of substantial capacity is provided for carrying small pieces of clothing and other personal effects, and wherein men's suits or ladies' dresses are mounted on garment hanger means disposed on the outside surface of the box cover to be held in place by a flexible yielding flap or apron which forms one outer side wall of the luggage.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate two complete examples of the physical embodiment of the invention constructed according to the best modes so far devised for the practical application of the principles thereof, and in which:

Figure 1 is a perspective view of a piece of luggage embodying this invention;

Figure 2 is a cross section view taken through Figure 1 on the plane of the line 2—2;

Figure 3 is a perspective view of the luggage open, showing the internal construction; and

Figure 4 is a side elevation of a modified embodiment of the invention.

Referring now more particularly to the accompanying drawings, in which like numerals indicate like parts throughout the several views, the numeral 5 designates generally a solid walled box, which forms the body of the luggage and is

composed of a bottom wall 6, end walls 7, a top wall 8, and a side wall 9. The open opposite side of the box is closed by a cover 10 hinged to the bottom wall as at 11.

For a purpose to be hereinafter described, the outer free edge of the cover terminates short of the top wall 8 and has a rounded molding 12 or other suitable non-creasing garment support attached thereto.

Detachably mounted on the outer face of the cover 10, adjacent its hinged edge, is a garment hanger means 13, which in the embodiment illustrated in Figures 1 to 3 inclusive, is of the conventional men's coat hanger type to carry men's suits and in the embodiment shown in Figure 4, of that type more particularly adapted to the carrying of ladies' dresses. This is the only distinction between the two modifications illustrated. Garments draped on the hanger means 13 extend out across the outer face of the cover 10 and are folded over the outer free edge 12 to be brought back across the inner face of the cover where they are held in place by a retaining flap 14, detachably secured to the inner surface of the cover in any suitable manner. Thus, with the garments properly arranged as described, the cover 10 may be opened and closed to afford access to the interior of the box without in anywise disturbing the neat arrangement of the garments.

From the description thus far, it is seen that the garments carried as described are partially within the box and partially outside the box, with the space left between the outer free edge of the cover and the adjacent top wall of the box accommodating the portions of the garments folded over the edge of the cover.

To cover the portions of the garments on the exterior of the box, a flexible apron 15 is permanently hingedly attached to the box adjacent the hinged edge of the cover as at 16. Preferably, the flexible apron 15 is composed of the same material which forms the outer covering 17 for the box, the outer covering, of course, being glued and permanently secured to the walls of the box, as is customary.

The free edges of the apron 15 are secured to the adjacent walls of the box by continuous interlocking fastening means 18 having one part sewed to said edges of the apron and its complementary part sewed to the covering 17 and extending beyond the actual walls of the box as clearly shown in Figures 2 and 3.

The conventional sliders (not shown) for interlocking the fastening means 18 are located at the top of the luggage when the interlocking

fastening means have been engaged, where they are covered by a flap 19 sewed to the apron and extending across the top wall 8.

To hold the flap 19 down in its closed position, 5 a lock is provided, one section 20 of which is carried by the flap and the other section 21 being secured to the top wall as shown. The lock may be of any desired construction or may be of the type shown and described in the copending application of George Henry Wheary, Serial No. 10 725,448, filed May 14, 1934.

To afford means for carrying the luggage, a handle 22 is fastened to the top wall 8, as shown, and inasmuch as the rounded edge 12 of the 15 cover 10, over which the garments are folded, is uppermost in the normal carrying position, it follows that there will be no tendency on the part of the garments to shift from their proper positions.

20 From the foregoing description taken in connection with the accompanying drawings, it will be readily apparent to those skilled in the art to which this invention appertains, that novel means for carrying men's suits and ladies' dresses 25 are provided and that an extremely light weight construction is obtained and added convenience in packing and unpacking results.

What I claim as my invention is:

1. Hand luggage of the character described, 30 comprising a solid walled box having one open side and a hinged cover disposed over said open side, means on said cover to carry garments in neatly folded arrangement with part of the garments on the outside of the cover, a flexible apron 35 to close the open side of the box and hold the portions of the garments on the exterior of the box cover flat against the cover, an outer surfacing of material similar to that of which the apron is made permanently fixed to the walls of the 40 box, means permanently attaching one edge of the apron to the box, and continuous interlocking fastening means to secure the remaining edges of the flexible apron to the box, said interlocking fastening means comprising two cooperating parts one of which is permanently fixed to 45 said remaining edges of the apron and the other of which is permanently fixed to the outer surfacing adjacent the periphery of the open side.

2. Hand luggage of the character described, 50 comprising a solid walled box of substantial capacity and having a hinged cover, means on said cover to carry garments in neatly folded arrangement with part of the garments disposed across the outside of the cover, a flexible apron permanently connected to the box adjacent the 55 hinged edge of the cover and arranged to fit over the garments on the outside of the cover to hold the same in place, and continuous interlocking fastening means to secure the free edges of the apron to the box, said fastening means 60 having a part permanently mounted on the box and another part fixed to the apron.

3. Hand luggage of the character described, 65 comprising a light weight solid walled box of substantial capacity, means on an outer wall of the box to carry garments in neatly folded arrangement with portions of the garments extending across said outer wall of the box, a flexible apron adapted to fit over the garments on the outside of the box and to form an outer wall 70 of the luggage, means to permanently secure one edge of the apron to the box and continuous interlocking fastening means to secure the remain-

ing edges of the apron to the box, said interlocking fastening means comprising two cooperating sections adapted to be interlocked, one of said sections being permanently mounted on the box and the other being permanently mounted on the apron.

4. Hand luggage of the character described, 10 comprising a light weight solid walled box having a hinged cover, garment hanger means attached to the exterior of the cover adjacent its hinged edge and adapted to have garments draped thereon, the outer free edge of the cover being adapted to have such garments folded thereover so that the garments are partially within the box and partially on the exterior of the cover, a flexible apron permanently connected to the box adjacent the hinged edge of the cover and arranged to fit over the cover across the portions of the garments on its exterior and to provide an outer 15 wall of the luggage, and continuous interlocking fastening means mounted on the side walls of the box and the free edges of the apron for connecting the free edges of the apron to the box.

5. Hand luggage of the character described, 20 comprising a light weight solid walled box having a hinged cover with its free edge spaced from the adjacent wall of the box to provide a space therebetween, garment hanger means on the exterior of the cover adjacent its hinged edge adapted to have garments draped thereover to 25 extend across the outer face of the cover and be folded over the outer free edge thereof to be partially received within the box, the portions of the garments folded over the outer free edge of the 30 cover being accommodated by the space between said edge of the cover and the adjacent wall of the box, a soft yielding flexible apron to cover the portions of the garments on the exterior of the box cover and provide an outer wall of the luggage, said apron being permanently attached to the box adjacent the hinged edge of the box cover and being of such size that its free edges 35 lie adjacent the side walls of the box, and continuous interlocking fastening means mounted on said side walls of the box and the free edges 40 of the flexible apron to readily detachably hold the apron closed over the box cover and forming an outer wall of the luggage.

6. Hand luggage of the character described, 45 comprising a solid walled box having a hinged cover, garment hanger means on the outer face of the cover adjacent its hinged edge adapted to receive garments in position to be folded over the outer free edge of the cover, whereby said garments are partially on the outside of the cover 50 and partially within the box, a flexible apron permanently fixed to the box adjacent the hinged edge of the cover, and of a size to fit snugly across the hinged cover to hold garments thereon against shifting and to form an outer wall 55 of the luggage, continuous interlocking fastening means mounted on the free edges of the apron and the adjacent side walls of the box to hold the apron in its closed position over the box cover, said interlocking fastening means including sliders movable along the fastening means to open 60 and close the same and adapted to come to rest at a predetermined point when the apron is secured in its closed position, a flap carried by the flexible apron to extend over the sliders, and lock means on the said flap and the adjacent wall 65 of the box to secure the flap to the box.

GEORGE HENRY WHEARY.
